UNITED STATES PATENT OFFICE

2,555,773

BALCONY SLEEPER

Joseph C. Williams, Santa Monica, Calif.

Application October 5, 1946, Serial No. 701,572

5 Claims. (Cl. 5—10)

1

This invention is a balcony or porch sleeper providing for those desiring to sleep outdoors, and is a provision for sun bathing.

An object of the invention is to provide an outdoor sleeper which incorporates an attractive and narrow balcony which will receive architects' approval in that it is compact in width and length to avoid cumbersome appearance and which is large enough for a bed unit including a laterally shiftable truck and an applied bed element.

Another object of the invention is to provide a balcony bed unit in combination with a wall having a window into and from which a projecting portion of the bed may be easily shifted for access by the user, and be moved out from the window while in actual use or is empty so that, when desired, the window may be closed.

Also, an object of the invention is to provide a balcony bed unit which is materially wider than the supporting balcony to afford ample resting area; the bed being of such width that in its outer position the wall side of the bed still overhangs the window sill, the overhang being nearly equal to the thickness of the wall. In this connection it is an aim of the invention to employ the window sill as a safe under support for the inwardly shifted bed side while a person may be sitting on or applying downward pressure to it.

Further, an object of the invention is to provide that the inwardly shifted bed unit will not accidentally shift out from the sill while a person is sitting on the intruded side of the bed or is climbing onto the bed for reclining thereon. A provision includes means which will effect holding cooperation of the bed at the window sill as soon as weight of the individual is placed on the side of the bed interposed over the inner side of the sill. Another purpose is to provide a yieldable means which will automatically release the bed from the sill when the effective load is shifted from the inner side of the bed—as when the occupant moves his weight to the center of the bed.

Modifications and adaptations may be resorted to within the scope, spirit and principles of the invention as claimed in conclusion hereof.

Figure 1 is a sectional plan of the wall, the closed window and the bed in outer position on the balcony.

Figure 2 is a vertical, sectional elevation of the end of the bed unit intruded over the window sill.

As here disclosed a wall W has a window open-

ing frame F of suitable height and long enough to permit interposition of the near side portion of a bed having a stiff bottom board 2 over the window sill S, Fig. 2. Bedding 3 of any desired make-up is secured to the top of the board and the latter is substantially counterbalanced by a spring hinge device 4, or its equivalent, fixed to the outer, upper corner of a substantial truck preferably in the form of a box 5 for bedding or night clothing, etc. It will be seen that the bed board constitutes the top closure for the open-top box truck and can be tilted up and outward from the sill for access to the trucks; which may if desired have a folding leaf 5a at one side. The truck is slidably mounted, by way of rollers 6, on parallel guide tracks 7 fixed on the floor of a balcony 8, which in carrying out one object of this invention, is slightly longer than the bed (which is confined against end motion) and has a width sufficiently wider than the truck to permit the bed and truck unit to shift bodily from an inner position, Fig. 2, to the outer position, Fig. 1, so that the bed occupant may sleep wholly outdoors and enabling the window sash X to be closed. A stop 9 will limit outward shift of the truck, and an inner stop 10 will limit inward shift thereof.

Means are provided to prevent the bed from shifting outward while an individual may be sitting on or applying sufficient weight to the side portion of the bed at the time that it is located over the sill S. This means may be in the form of any desired compressible or cushioning device which will normally hold the bed board 2 just high enough to clear the sill S as the empty or unloaded inner side of the bed is moved to or from the sill. The elevating or cushioning means here includes a spring device 11 on the truck and supporting the board in the desired elevated position. When the inner, bed side is in a position over the sill S it will clear the sill for free movement until enough downward pressure is applied to set the board on the sill face and the resultant friction will be enough to retain the bed at the sill until the effective load is removed—as will be the case when the occupant climbs or rolls to the center of the bed, when the spring device 11 will automatically release the board from the sill. To positively insure interlock of the bed to the sill there is shown a rigid cleat 12 on the under face of the board 2 and which normally clears the sill top for free shift of the bed unit. When a load is applied to the bed part over the sill the cleat descends

enough to lock inwardly against the sill shoulder Sh.

As soon as the bed board 2 is free the occupant of the bed can easily shift the whole bed unit out to the limit so that the window X may be closed.

The bed unit is in no manner hitched to the balcony structure and can therefore at any time be bodily lifted from the balcony for storage in extremely bad weather.

It is understood that the elevating cushion may take any of equivalent functioning means and the spring device 11 may be attached to the bed board 2 if preferred.

What is claimed is:

1. The combination, with a wall having a window, of a support outside said wall and adjacent said window, a truck carried upon said support for movement toward and away from said window, a bed structure having one edge hinged to and supported by said truck, the other edge of said bed structure projecting through said window and over the sill, yielding means on said truck supporting said other edge of said bed structure above the window sill when said bed is unoccupied, and means on said bed structure adapted to engage said window sill through depression of said yielding means when said bed is occupied, to prevent accidental outward shift of said bed structure.

2. The combination of claim 1; and means limiting the outward movement of the truck at a position where the extending side of the bed will still be in a position over the outer portion of the sill.

3. The combination of claim 1; said means including a lug on the free side of the said structure adapted to interlock with the window sill when the structure is depressed.

10 4. The combination of claim 1; the truck being of open-top box form and the bed structure forming a closure therefor.

15 5. The combination of claim 1; the bed structure being substantially counterbalanced for easy lift and covering the truck when in lowered position on the truck.
